(74) *Attorney, Agent, or Firm* — Honigman Miller Schwartz and Cohn LLP

(57) **CLAIM**

I claim the ornamental design for a mold, as shown and described.

DESCRIPTION

FIG. 1 is a perspective view of a mold in accordance with my new design;

FIG. 2 is a top plan view of the mold of FIG. 1;

FIG. 3 is a front elevation view of the mold of FIG. 1;

FIG. 4 is a side elevation view of the mold of FIG. 1, an opposite side elevation view being identical;

FIG. 5 is a rear elevation view of the mold of FIG. 1;

FIG. 6 is a bottom plan view of the mold of FIG. 1;

FIG. 7 is a perspective view of another mold in accordance with my new design;

FIG. 8 is a top plan view of the mold of FIG. 7;

FIG. 9 is a front elevation view of the mold of FIG. 7;

FIG. 10 is a side elevation view of the mold of FIG. 7, an opposite side elevation view being identical;

FIG. 11 is a rear elevation view of the mold of FIG. 7; and,

FIG. 12 is a bottom plan view of the mold of FIG. 7.

The broken lines shown throughout the drawing figures depict portions of the mold that form no part of the claim.

1 Claim, 4 Drawing Sheets
